UNITED STATES PATENT OFFICE.

LOUIS STEPHEN DOYLE, OF AUSTIN, TEXAS.

ORTHOPEDIC APPLIANCE.

1,401,056.

Specification of Letters Patent. Patented Dec. 20, 1921.

Application filed February 9, 1921. Serial No. 443,615.

To all whom it may concern:

Be it known that I, LOUIS STEPHEN DOYLE, a citizen of the United States, and a resident of Austin, in the county of Travis and State of Texas, have invented certain new and useful Improvements in Orthopedic Appliances, of which the following is a specification.

My invention relates to improvements in 10 orthopedic appliances for use with the spine.

The object of the invention is to provide an improved appliance of this character which is adapted to exert a pressure upon the spinal column in the lumbar region so 15 as to maintain the vertebræ in proper position and relation, thereby relieving the associated organs and muscles of abnormal strains and restoring these portions of the body to normal position and condition thus 20 remedying and eliminating the variety of diseases and ailments incident to such abnormal positions and conditions of these portions of the body.

Other objects and advantages of the invention reside in certain novel features of construction, combination and arrangement 25 of parts which will be hereinafter more fully described and particularly pointed out in the appended claims, reference being had 30 to the accompanying drawings forming part of this specification and in which:

Figure 1 is a view in elevation illustrating the appliance in use;

Fig. 2 is a detail view in elevation of the 35 appliance detached;

Fig. 3 is an end elevational view thereof;

Fig. 4 is a side elevational view of a slightly modified form;

Fig. 5 is a detail view in transverse section on line 5—5 of Fig. 4;

Fig. 6 is a rear elevational view of another form of the invention; and

Fig. 7 is an end elevational view of another modified form of the invention.

Referring to the drawings wherein for the sake of illustration is shown the preferred embodiment of the invention it will be seen by referring to Fig. 1 that the appliance, designated generally at 10, is utilized in the 45 lumbar regions of the spine and is urged against the spine by means of a waist line belt 11 which may be the belt normally worn by the user.

In all forms of the invention there is included a plate or body portion 12 upon which are carried in spaced parallel relation

pressure ribs 13 symmetrically arranged with respect to the longitudinal axis of the appliance and with respect to the axis of the spinal column and adapted to exert uniform 60 pressure on the opposite sides of the spinal column.

Means is provided for securing the appliance in proper position upon the wearer and preferably consists of a pair of fasteners 15 65 preferably in the form of resilient hooks adapted to coöperate with the body garment of the wearer and a single centrally disposed fastener 16 also in the form of a resilient hook and adapted to embrace and be 70 secured to the belt 11. Below the central hook 16 and the belt 11 a transverse bar 17 is arranged and serves as a guard to prevent the appliance from being displaced upwardly and incidentally serves to brace the 75 lower end of the back.

In the form of my invention shown in Fig. 2, the body portion or plate 12 is provided with an extension designated at 18, the sides of which taper along straight lines, 80 as at 19, and having a V-shaped recess therein, as shown.

In the form of my invention shown in Fig. 4, the plate or body portion 12 is provided with an extension 22 reduced on curved lines 85 23 so as to terminate in a reduced end 24.

In the form of my invention shown in Fig. 6, the reduced extension is designated at 25, and is rectangular the same as the body portion or plate 12 although on a reduced scale.

In all forms of the invention the reduced extension is disposed in use between the hip bones and centers the appliance and also enables the pressure ribs 13 which extend 95 along the extensions as well as along the body portion to exert their action in this region.

In the form of my invention shown in Fig. 8, which may have its extension designated at 26 formed in any of the above described manners the plate or body portion 12 and the ribs 13 are provided at their upper end with curved portions designated at 12^a and 13^a, respectively. This curved formation may be necessary in certain instances in order that the pressure ribs may properly contact with the vertebræ of the spine. Means for securing the appliance in position and the action of the appliance is in 110 all respects similar to the embodiments above described.

I claim:

In an orthopedic appliance of the character described, a plate having an extension, the extension having its sides tapered so as to be reduced, a pair of pressure ribs extending longitudinally of the plate and the extension and secured thereto, said pressure ribs being symmetrically disposed with respect to the longitudinal axis of the plate and extension and adapted to exert pressure

upon the spinal column to restore it to normal position and condition, and means for securing the appliance in position comprising a pair of resilient hooks and a centrally disposed resilient hook coöperable with the belt, and a transverse bar adapted to be arranged below the belt of the wearer to prevent the appliance from moving upwardly.

LOUIS STEPHEN DOYLE.
